UNITED STATES PATENT OFFICE.

MARIE JOSEPH TALANSIER, OF PARIS, FRANCE.

APPARATUS FOR FIXATION OF LIQUIDS.

1,042,171.

Specification of Letters Patent.

Patented Oct. 22, 1912.

Application filed October 1, 1909. Serial No. 520,567.

To all whom it may concern:

Be it known that I, MARIE JOSEPH TALANSIER, a citizen of the Republic of France, residing at Paris, France, have invented certain new and useful Improvements in Apparatus for Fixation of Liquids, of which the following is a specification.

My invention relates to the fixation of compound liquids, such as milk, by the process of emulsifying or pulverizing the larger globules therein and thereby rendering the liquid homogeneous by breaking up these nuclei or cells of matter which are normally floating in or in a state of suspension in, such liquid. The result is a fixed stable, homogeneous fluid which, in the case of milk, can be allowed to stand for a long time without any separation of cream, or fatty particles or other constituents from the main body of the fluid. This fixation is usually effected by forcing the fluid, such as milk, under great pressure through a number of capillary openings in a diaphragm or partition. The partitions have heretofore been made of metal. Among the practical difficulties encountered with such diaphragms have been the wearing of the metal about the small holes so that the same, or some of them, have soon become large enough to permit the fatty globules to pass without being broken up, and the oxidation of the surfaces of the metal, such particles of oxid being torn away by friction of the fluid in the capillary passages, mingling with the fluid and destroying the purity of the treated product. I have invented a form of apparatus which avoids these and other difficulties heretofore encountered and contains novel features of practical advantage. The best form of apparatus at present known to me embodying my invention, is illustrated in the accompanying two sheets of drawings in which,

Figure 1 is a longitudinal axial section of the device. Fig. 2 is an enlarged cross section on line 2-2 of Fig. 1. Fig. 3 is an enlarged cross section of one of the interlocking perforated rings, and Fig. 4 is a side view of the device, with a pump in operative connection therewith.

Throughout the drawings like reference figures indicate like parts.

A is a tube, the lower portion of which is provided with perforations a. Its lower end is closed in any convenient manner as by

stopper B held in by screw thread b. On this tube A as a support are assembled a series of rings C, the adjacent faces of which are preferably provided with interlocking, annular projections or shoulders and depressions or recesses c. These rings C are each provided with radial perforations in line with certain of the perforations a in tube A. These perforations are preferably cone shaped and into them fit cone shaped bits or blocks D of sapphire or other jewels, hard glass or other material of extreme hardness and close and even texture. These blocks D are preferably arranged with their apices pointing inward and they are provided with capillary passages d extending from base to apex. The perforated tubular structure so formed is placed in the cylinder L, formed of a strong casting open at both ends, and held centrally therein so as to form an annular chamber E, by reason of the fact that tube A is tightly fitted in the gland F of the stuffing box which closes the upper end of cylinder L. This stuffing box is formed by said gland F, a series of packing rings located in an annular recess in the inner wall at the upper end of cylinder L, and the cap nut K screwed on to the upper end of cylinder L, and bearing on the gland F. Preferably the packing rings comprise a leather gasket or ring H, an ébonite gasket or ring I and a bronze ring J. The tube A has an external screw thread g on the portion protruding through stuffing box cap K and a threaded nut G meshes with this thread g.

M is a strong flange at the base of cylinder L, by which it may be connected to any suitable liquid pressure producing apparatus, such as pump P, through pipe p. The inlet to annular chamber E is through passage N, and the outlet through the perforated tubular structure to the orifice O of tube A, which is connected to any suitable receptacle, not shown.

In operation the milk or other fluid is forced under great pressure by pump P into the annular chamber E, and through the capillary passages d, and perforations a into tube A, and thence out through the discharge opening O. If any of the conical jewels or blocks D wear so that the opening d becomes too large, the device is disconnected, the nut G and cap K are unscrewed, the gland F, and the tube A are withdrawn, the rings C taken off, new ones substituted

for the defective ones, and the parts replaced. The defective jewel or jewels D, may be removed from the rings C so taken out, new jewels with capillary passages of proper size may be set in said rings, and the rings used over again. In reassembling the parts the rings C are compressed together between stopper B at one end of tube A, and gland F, forced down by nut G and cap K, so as to form liquid-tight joints between the rings.

The advantageous characteristic of my invention is the manner in which all stresses developed in its use tend to compress and force the parts together so as to reduce the possibility of leakage, instead of opening seams to form leaks. The pressure tends to force stopper B against the end of tube A, and against rings C. Rings C are forced against one another and against the end of gland F. The cone shaped jewels or blocks D are driven more snugly and tightly into their cone shaped seats in rings C as the pressure of the liquid increases and so, the greater the pressure the tighter these joints become. All parts of the tubular structure constituting the perforated diaphragm are subjected to compression strains, only, so that fractures are much less likely to occur than would be the case if they were under tensile strains. While the portions of the diaphragm having the capillary passages have the great hardness necessary to withstand wear, their consequent lack of tensile strength is compensated for by the metal supporting structure of tube A and rings C.

Other advantages of my invention comprise economy in use, ease of repair, durability of the jeweled capillaries, freedom from liability to foul the liquid treated and convenience in assembling parts.

It is evident that various changes could be made in the details of construction herein illustrated and described without departing entirely from the substance of my invention. Various of the features of improvement herein set forth could be dispensed with and others alone employed and various modifications in the forms and proportions of parts could be made so long as the principle of the invention were retained in whole or in part. Thus the cylindrical form of chamber might be dispensed with and other forms employed. Other forms of perforated diaphragm through which the fluid must go in passing from the inlet of the chamber to the outlet might also be substituted for the specific built up cylinder of interlocking rings here shown.

Having, therefore, described my invention, I claim:—

1. The combination of a series of radially perforated rings assembled to form a cylinder, conically shaped bits of hard material provided with capillary passages from

base to apex of the cone set in said perforations, and means for forcing a liquid through said capillary passages.

2. The combination of a series of radially perforated rings assembled to form a cylinder, 70 conically shaped bits of sapphire provided with capillary passages from base to apex of the cone set in said perforations, and means for forcing a liquid through said capillary passages.

3. The combination of a series of radially perforated rings assembled to form a cylinder, conically shaped bits of hard material provided with capillary passages from base to apex of the cone set in said perforations, and means for forcing a liquid through said capillary passages, the adjacent faces of said rings being provided with interlocking projections and recesses.

4. The combination of a series of radially perforated rings assembled to form a cylinder, conically shaped bits of hard material provided with capillary passages from base to apex of the cone set in said perforations, and means for forcing a liquid 80 through said capillary passages, together with a supporting metal tube for said ring, closed at one end and having openings in line with the openings in the rings placed thereon.

5. In an apparatus for fixing milk and other fluids, a diaphragm formed of material of great strength having conically shaped perforations, conical bits of material of great hardness set in said perforations having capillary passages from base to apex, and means for forcing the fluid to be fixed through said capillary passages from the base toward the apex of each cone.

6. The combination of a cylinder having 105 an inlet opening at one end, a perforated tubular structure comprising a series of interlocking radially perforated rings inserted into said cylinder through its other end and forming a liquid-tight joint therewith, and a stopper for the inner end of said tubular structure, together with bits of sapphire provided with capillary passageways set in the 110 perforations of the rings.

7. The combination of a cylinder having 115 an inlet opening at one end, a perforated tubular structure comprising a series of interlocking radially perforated rings assembled upon a perforated tube inserted into said cylinder through its other end and forming a liquid-tight joint therewith, and a stopper for the inner end of said tubular structure, together with bits of sapphire provided with capillary passageways set in the 120 perforations of the rings.

8. The combination of a cylinder having 125 an inlet opening at one end, a perforated tubular structure comprising a series of interlocking radially perforated rings inserted into said cylinder through its other end and

forming a liquid-tight joint therewith, and a stopper for the inner end of said tubular structure, a stuffing box in the end of the cylinder through which the tubular structure is inserted, and means for compressing the rings between the gland of said stuffing box and the above mentioned stopper, together with bits of sapphire provided with capillary passageways set in the perforations of the rings.

9. The combination of a cylinder having an inlet opening at one end, a perforated tubular structure comprising a series of interlocking radially perforated rings assembled upon a perforated tube inserted into said cylinder through its other end and forming a liquid-tight joint therewith, and a stopper for the inner end of said tubular structure, a stuffing box in the end of the cylinder through which the tubular structure is inserted, and means for compressing the rings between the gland of said stuffing box and the above mentioned stopper comprising a nut threaded on the projecting portion of the perforated tube, together with bits of sapphire provided with capillary passageways set in the perforations of the rings.

10. The combination of a cylinder having an inlet opening at one end, a perforated tubular structure comprising a series of interlocking radially perforated rings inserted into said cylinder through its other end and forming a liquid-tight joint therewith, and a stopper for the inner end of said tubular

structure, together with conically shaped bits of sapphire provided with capillary passages extending from apex to base set in the perforations of the rings, the apices pointing inward.

11. The combination of a cylinder having an inlet opening at one end, a perforated tubular structure comprising a series of interlocking radially perforated rings inserted into said cylinder through its other end and forming a liquid-tight joint therewith, and a stopper for the inner end of said tubular structure, together with conically shaped bits of sapphire provided with capillary passages extending from apex to base set in the perforations of the rings, the apices pointing inward, and means for forcing liquid under pressure into said cylinder through the inlet end thereof.

12. The combination of a metal cylinder having an inlet opening at one end, a built up tubular structure composed of an assemblage of radially perforated rings inserted into said cylinder through its other end and forming a liquid-tight joint therewith, bits of material of great hardness set in said radial perforations and provided with capillary passages extending through them radially to the tubular structure, and a stopper for the inner end of said tubular structure.

MARIE JOSEPH TALANSIER.
